METAL CONTAINER

William F. Punte, Syracuse, N. Y., assignor to
Continental Can Company, Inc., New York,
N. Y., a corporation of New York

Application December 10, 1934, Serial No. 756,872

2 Claims. (Cl. 220—61)

The invention relates to new and useful improvements in an easy opening container wherein the cover is secured to the container body by a sealing strip.

5 The invention is an improvement in the containers disclosed by William F. Punte in Letters Patent #1,849,312, granted March 15, 1932, and application Serial No. 742,991, filed September 6, 1934. In the patent and application mentioned above, the container includes a body portion which is offset adjacent one end thereof to form a shoulder, a cover having a depending skirt adapted to extend along the outer face of the body wall terminating substantially at said shoulder, a ring of sealing material engaging the shoulder at the lower edge of the skirt, and a metal sealing strip adapted to compress the sealing ring against the shoulder and the lower edge of the skirt.

20 An object of the present invention is to provide a container of the above type wherein the shoulder is so constructed as to allow the sealing material to be compressed much tighter without distorting the can body, thus making a 25 more effective seal than heretofore accomplished.

In the drawing—

Figure 1 is a plan view of the improved container;

30 Fig. 2 is a view in side elevation of the same;

Fig. 3 is an enlarged sectional view through the upper portion of the container with the sealing strip loosely applied and the sealing material in place;

35 Fig. 4 is a view similar to Fig. 3, but showing the strip tightly applied to compress the sealing material for establishing a seal, and

Fig. 5 is an enlarged sectional view of a container of the type shown in Figures 3 and 4, 40 showing a slight modification of structure.

The invention is directed to a container consisting of a body portion having an open end. The metal at the open end is rolled so as to form a hollow bead and conceal the raw edge of 45 metal. The body is provided with a bend in the wall thereof directly under the bead to form a shoulder on the outer face of the container which is disposed adjacent the bead. The cover is preferably provided with a depression which 50 fits within the beaded open end of the container body. The cover has a depending skirt which slips down over the outside of the body wall. Said skirt is turned back upon itself so as to provide a smooth thickened edge at its lower 55 end. A sealing ring or gasket is placed against

the shoulder in the body wall and against the lower end of the skirt which is on a line therewith, and a sealing strip is applied for securing the cover to the container and sealing the same.

5 The sealing strip has a portion underlying the cover, a portion extending vertically along the outside wall of the skirt to a point below the same, and a portion turned in at its lower end, which underlies the shoulder on the outer face of the container and sealing gasket placed thereagainst. When pressure is applied to the upper and lower faces of the sealing strip, the vertical portion thereof will be shortened and the gasket will be forced against the shoulder and compressed to form a tight joint for sealing the container. In the present invention, the shoulder formed in the body wall against which the gasket is compressed is of two or more thicknesses of metal whereby a rigid abutment is formed against which greater force may be applied for 10 making a tight seal without distorting the mouth of the can body.

15 Referring more in detail to the drawing, the improved container consists of a body portion 1 preferably made of metal and cylindrical in 20 form. To one end of the body portion is attached a closure end 2 which is secured thereto by a double seam 3. The outer end of the body wall is rolled or curled as indicated at 4. This forms a bead at the end of the body wall and 25 conceals the raw edge of metal. It also makes a smooth edge at the end of the body wall when the container is opened and strengthens the open end of the body so as to maintain its 30 rounded form.

35 In the preferred form of the invention shown in Figures 3 and 4 of the drawing, a portion of the body wall 5 is bent outwardly and the walls of said outwardly bent portion are brought into contact, thus forming a sealing shoulder 6. The 40 projecting portion thus formed is of two thicknesses of metal, and this provides a rigid abutment against which a sealing ring may be compressed, as later set forth. In forming the sealing shoulder 6, it is desired that it should be 45 so formed as to extend upwardly at a slight angle to the horizontal from the body of the container.

The container is closed by a cover 7. This 50 cover has a depression formed therein providing an inner wall 8 which extends down inside of and makes contact with the inner edge of the bead 4. The cover has a portion 9 which overlies the bead and a depending skirt 10. This depending skirt 10 is folded back upon itself

as indicated at 11. The folded skirt extends down outside of the body wall and along the outer face of the bead. The skirt is of such length that the lower edge 12 thereof is disposed at a slight distance below the inclined shoulder 6. An elastic sealing ring or gasket 13, preferably of rubber, and rectangular in cross section, is placed beneath the shoulder 6, and the lower edge 12 of the skirt 10 of the cover. 10 The cover 7 is secured to the container by means of a sealing strip 14, the ends of which overlap. One end is provided with a tongue or tab 15 which may be utilized for removing the sealing strip when it is desired to open the container. The sealing strip 14 is bent so as to provide a portion 16 which overlies and extends all the way across the portion 9 of the cover 7. This overlying portion is curved in the same direction as the portion 9. The sealing strip 14 15 has a vertical portion 17 which extends downwardly along the outer wall of the skirt 10 to a point below the skirt and the sealing gasket 13, and is provided with an inwardly projecting portion 18 at the lower edge thereof, which is 20 adapted to underlie the lower face of the sealing gasket. 25

The vertical portion 17 of the sealing strip 14 extends sufficiently below the lower edge of the skirt 10 of the cover to form a pocket to receive 30 and house the sealing gasket 13. When pressure is applied in a direction parallel with the wall of the container to the overlying portion 16 and the underlying portion 18 of the sealing strip, the vertical wall 17 of said strip will be shortened 35 and the gasket be compressed within the pocket provided therefor and forced against the inclined shoulder 6 and lower edge 12 of the skirt. Because of the additional strength given to the shoulder 6 by forming the same of two thicknesses of metal, a rigid abutment is provided 40 against which more force may be applied and a tighter seal may be effected without distorting the mouth of the can body.

In the modified form of the container shown 45 in Fig. 5, the bead at the upper end thereof is rolled inwardly instead of outwardly as disclosed in the form shown in Figures 3 and 4. The body wall beneath the bead is inset and the portion of the metal which forms the inclined shoulder consists of three thicknesses of metal 50 instead of two. This provides a sealing shoulder which is even more rigid than that shown in Figures 3 and 4.

When it is desired to open the container, the 55 tab or tongue is pulled and this will remove the sealing strip, exposing the sealing gasket which may be likewise removed. The cover can then be easily removed and replaced at will, and thus used for reclosing purposes.

It is obvious that minor changes in the details of construction and the arrangement of the parts may be made without departing from the spirit of the invention as set forth in the appended claims. 5

Having thus described the invention, what I claim as new and desire to secure by Letters Patent, is—

1. A metal container including in combination a body portion having the upper edge rolled 10 to form a hollow bead, said body portion being bent outwardly and having the walls of said outwardly projecting portion bent into contact to form a rigid double wall sealing shoulder, the lower face of which inclines upwardly and 15 outwardly, a cover for said container having a depending skirt adapted to extend over the container body and terminating slightly below the outer edge of the lower inclined surface of the sealing shoulder, a sealing gasket encircling the 20 container and adapted to engage said shoulder and the lower edge portion of said skirt, a metal sealing strip having a portion overlying the cover, a portion extending vertically along the skirt of the cover and sealing gasket, and a 25 portion projecting inwardly and adapted to underlie said gasket whereby when pressure is applied to the upper and lower portions of the sealing strip, the gasket will be forced against the sealing shoulder and compressed to form a 30 tight joint for sealing the container.

2. A metal container including in combination, a body portion having the upper edge thereof rolled to form a hollow bead, said body portion being bent outwardly and having the walls of 35 said outwardly projecting portion bent into contact to form a rigid double wall sealing shoulder, said sealing shoulder being disposed directly beneath said hollow bead and in contact therewith, the lower face of said shoulder being inclined upwardly and outwardly, a cover for said container having a depending skirt adapted to extend over the container body and terminating slightly below the outer edge of the lower inclined surface of the sealing shoulder, a sealing 40 gasket encircling the container and adapted to engage said shoulder and the lower edge portion of said skirt, a metal sealing strip having a portion overlying the cover, a portion extending vertically along the skirt of the cover and 45 the sealing gasket, and a portion projecting inwardly and adapted to underlie said gasket whereby when pressure is applied to the upper and lower portions of the sealing strip, the 50 gasket will be forced against the sealing shoulder and compressed to form a tight joint for sealing the container. 55
